UNITED STATES PATENT OFFICE.

ARTHUR DANBY, OF PHILADELPHIA, PENNSYLVANIA, ASSIGNOR TO THE IVINS, DIETZ & METZGER COMPANY, OF SAME PLACE.

DESIGN FOR CARPET.

SPECIFICATION forming part of Design No. 25,450, dated April 28, 1896.

Application filed March 23, 1896. Serial No. 584,551. Term of patent 3½ years.

To all whom it may concern:

Be it known that I, ARTHUR DANBY, a subject of the Queen of Great Britain, residing at Philadelphia, county of Philadelphia and State of Pennsylvania, have invented and produced a new and original Design for Carpet Fabrics, of which the following is a full, clear, and exact description, reference being had to the accompanying drawing, which forms a part of this specification.

My design, as shown in the drawing, consists in a new design for the body and border of a carpet fabric.

In the drawing, A represents the body, and B the border. The design of the body A consists, essentially, of a scroll, as shown in the drawing.

The border B has at the end contiguous to the body a figured border-line, as shown. The main body of the border consists of a light plain ground, which partially conceals a lighter groundwork of a scroll-pattern. This light ground terminates at its upper end in

an irregular form, and the border continues beyond in a solid dark-colored ground, upon which are placed various figures, as shown in the drawing. Upon the light-colored ground is a wreath of flowers suspended, having at its ends a spray of flowers hanging therefrom and a ribbon effect.

Having now fully described my invention, what I claim, and desire to protect by Letters Patent, is—

1. In a design for a carpet fabric, the body A, substantially as shown.
2. In a design for a carpet fabric, the border B, substantially as shown.
3. The design for a carpet fabric comprising the body A and the border B, substantially as shown.

In testimony of which invention I have hereunto set my hand.

ARTHUR DANBY.
